United States Patent Office

Des. 176,851
Patented Feb. 7, 1956

176,851

DOORKNOB

Glen Holland, Valley Forge, Pa.

Application June 7, 1954, Serial No. 30,843

Term of patent 14 years

(Cl. D50—3)

Fig. 1.

Fig. 2.

Fig. 3.

Fig. 1 is a side elevational view of a doorknob, showing my new design.

Fig. 2 is a face view of the doorknob.

Fig. 3 is a longitudinal sectional view thereof.

I claim:

The ornamental design for a doorknob, substantially as shown.
